UNITED STATES PATENT OFFICE.

HENRY B. TITUS, OF BROOKLYN, ASSIGNOR TO EDWARD TODD & CO., OF NEW YORK, N. Y.

DESIGN FOR A SIGN.

Specification forming part of Design No. 6,795, dated August 5, 1873; application filed August 1, 1873.

To all whom it may concern:

Be it known that I, H. B. TITUS, of the city of Brooklyn, county of Kings, State of New York, have invented a Design for a Sign, of which the following is a specification:

My design is fully represented in the accompanying drawings, to which reference is made.

It consists of a sign made oval in form, of wood or metal, in outline, with a model or design of a pen suspended in its center, as shown.

In the drawing, A represents the frame; B, the space; and C, the pen.

I propose to place the dealer's name on one

portion of the sign, the style of his business on the other portion, and the name of the manufacturer of the article suspended or of the article itself in the center, on it, thereby combining two signs in one.

What I claim as my invention is—

The design for a sign, as shown and described.

HENRY B. TITUS.
